 1 Claim. (Cl. 78—21)

This invention relates to a forging machine in which the tool carriers consist of connecting rods which are spaced around the periphery of the workpiece and are driven by eccentrics or the like and which slide in radial guides of a suitably disc-shaped bearing body which is rotatable about the workpiece axis and participates in the swing movement of the connecting rods. In known machines of this type, the disc-shaped bearing body has been freely rotatable and has only been driven by the connecting rods themselves to perform an oscillating swing movement about the workpiece axis. This guidance and mounting of the connecting rods has proved satisfactory because the construction is extremely simple. Nevertheless the known construction requires improvement. The mere drive of the bearing body by the connecting rods results in relatively high wear at the guide faces in the bearing body and at the connecting rods. The resulting increased guide play adversely affects the working accuracy. A replacement of the worn connecting rods and of the bearing body is difficult because large, heavy and expensive parts of construction are concerned. The invention eliminates this disadvantage.

The invention resides essentially in that the bearing body has an oscillating drive imparted thereto from the eccentric heads of the connecting rods. The connecting rods have no longer the function of driving the bearing body during their swing movement but merely perform a reciprocating movement in a guide which performs inherently the same movement as the connecting rods so that there can be no canting and the wear of the guides in the bearing body and the connecting rods is minimized.

A particularly simple construction for the drive of the bearing bodies from the eccentric heads is obtained by rigidly affixing forked drivers to the bearing body, the prongs of which slide on opposite guide faces of the eccentric head which are parallel to the connecting rod. These drivers may be removable to enable their replacement.

An illustrative embodiment of the invention is diagrammatically shown in the accompanying drawing, in which

FIG. 1 is a horizontal sectional view showing a forging box of a forging machine, taken on line I—I of FIG. 2,

FIG. 2 is a vertical sectional view taken on line II—II of FIG. 1 and showing a portion of the forging box; and

FIG. 3 is an exploded view of the two-part bearing body.

The driving eccentric shafts 1 are eccentrically mounted

2

in rotatably adjustable bushings 3 in the forging box 2. A rotary adjustment of the bushings 3 will displace the axes of the shafts 1 so that the stroke position of the connecting rods 4 and with it the depth of penetration of the tools (not shown) which can be affixed to the free end of the connecting rod, into the workpiece can be varied. The workpiece is fed in a vertical direction between the hammers formed by the connecting rods 4 and the tools and may be rotated about its axis at the same time.

To guide the connecting rods 4 a two-part, ring-shaped bearing body 5 is mounted in the forging box 2 for rotation about the workpiece axis. This bearing body 5 has radial guides 6 for slidably receiving the connecting rods. The bearing body 5 has forklike drivers 7 rigidly affixed thereto, the prongs 8 of which slide on opposite guide faces 9 of the eccentric head 10, which guide faces are parallel to the connecting rod 4. During the movement of the eccentric head only the movement thereof in the peripheral direction, with respect to the workpiece axis, will be transmitted by the drivers 7 to the bearing body 5 so that the same is driven to perform an oscillating swing movement about the workpiece axis and the guides 6 assume always the correct position for the connecting rods because the guides are rigidly affixed to the bearing body and, therefore, oscillate therewith and this oscillating motion is caused by the same eccentric drive 1, 10 which oscillates the connecting rods.

What I claim is:

A forging machine for a workpiece which comprises connecting rods adapted to carry tools, said connecting rods being spaced around the periphery of the workpiece and extending in a radial direction with respect to the workpiece axis, eccentrics, eccentric heads connecting said eccentrics to said connecting rods to impart to the latter an oscillating motion in peripheral and radial directions with respect to the workpiece axis, a bearing body mounted for rotation about the workpiece axis, radial guides mounted in said body and slidably receiving said connecting rods, and means for imparting to said bearing body an oscillating angular motion in unison with said motion of said connecting rods in said peripheral direction while enabling a movement of said connecting rods relative to said bearing body in said radial direction, said means comprising forked drivers rigidly affixed to said bearing body and having prongs, said eccentric heads being formed with opposite guide faces extending parallel to the respective connecting rod and slidably engaged by said prongs.
